UNITED STATES PATENT OFFICE.

CHARLEY C. JONES, OF CEDAR VALE, KANSAS.

MAIL-CATCHER.

1,243,945.

Specification of Letters Patent. Patented Oct 23, 1917.

Application filed July 11, 1916. Serial No. 108,595.

To all whom it may concern:

Be it known that I, CHARLEY C. JONES, a citizen of the United States, residing at Cedar Vale, in the county of Chautauqua and 5 State of Kansas, have invented certain new and useful Improvements in Mail-Catchers, of which the following is a specification.

This invention relates to mail bag transferring devices, and aims primarily to simplify and increase the efficiency of devices 10 of this character.

A further object of the invention is to provide a device adapted to be used upon a mail car for collecting pouches arranged 15 beside a track, which is constructed and arranged in such manner as to positively hold the bag in the transferring operation, whereby loss of the sacks is obviated.

A still further object of the invention is 20 to provide a device of this character and for the purposes set forth which is of simple construction, which is composed of but few inexpensive and readily assembled parts, all so constructed and arranged as to prevent 25 wear, breakage or derangement of the same, which is capable of being moved when not in use to occupy but small space, and which will prove thoroughly efficient in the attainment of the ends for which it is designed.

With these objects in view, together with others which will appear as the description proceeds, the invention resides in the novel formation, combination, and arrangement of 35 parts, all as will be described more fully hereinafter, illustrated in the drawings, and particularly pointed out in the claims.

The invention will be best understood by 40 reference to the accompanying drawings, wherein:

Figure 1 is a sectional plan view of a mail bag collecting device, the same being shown in the position it would assume when ready to engage and grab a bag;

Fig. 2 is a longitudinal vertical sectional view taken substantially upon the line 2-2 of Fig. 1;

Fig. 3 is a fragmentary sectional view taken through the standard for supporting the arm;

Fig. 4 is a rear elevation of what is shown in Fig. 3;

Fig. 5 is a detail perspective view of one of the bag grabbing ends;

Fig. 6 is a plan view of a mechanism for

supporting a bag upon a car to be delivered to a mechanism beside a track; and

Fig. 7 is a side elevation of what is shown in Fig. 6.

The invention comprehends generally the 60 arrangement of a catching device either upon a car or beside the track, by means of which bags may be interchanged. The invention also comprehends an improved means for properly supporting the sacks, either upon 65 a car or beside the track so that the operation of the grabbing means may be facilitated. In the present instance, I describe the catching and holding mechanism as used upon the car only, but it is to be understood 70 that similar devices are arranged beside the track, whereby interchanging of the mail sacks is carried out.

Referring now more particularly to the drawings, 10 indicates a standard, which is 75 secured adjacent the doorway of a car upon a suitable base 11. Socketed within the standard 10 is a rod 12, which carries an angularly projecting arm 13. The upper edge of the tubular standard 10 is provided 80 with a notched portion 14 within which is adapted to engage a detent 15. The edges of the detent and notched portion are rounded, as shown in Fig. 4 of the drawings, so that the arm 13 when contacted, will swing 85 laterally and the detent 15 will ride up and out of the notched portion 14. The arm 13 is normally held projected laterally from the car. The arm is also hinged as at 16 to permit of the same swinging downwardly 90 adjacent the standard when not in use. A guy rod 17 connects the free end of the upper end of the rod 12.

A housing 18 is secured to the outer extremity of the arm 13. This housing is relatively shallow and is widened at its outer end as shown. A door 19 is arranged in the housing to permit of access being had to the interior thereof.

Pivoted as at 20 to the opposite lateral 100 sides of the housing and adjacent the outer extremity thereof, are grabber arms 21. These arms project for the greater portion of their length beyond the housing and their inner ends are connected as by links 22 to 105 a plate 23 arranged at the rear portion of the housing. A contractile spring 24 is connected at one end to the plate 23 and at its other end to a bolt or pin 25 extending through the arm 13 at the innermost end 110

thereof. The spring 24 extends within the hollow arm 13 and is adapted to draw inwardly upon a plate 23 and to rock the arms 21 toward each other at their outer ends.

A trigger 26 is pivoted as at 27 to the outer end of the housing and midway between the arms 21. The outer extremity of the trigger is provided with oppositely extending arcuate guide members 28, and the inner end of the trigger extends within the housing. Contractile springs 29 connect the inner end of the trigger at opposite points with the housing, the arrangement yieldably maintaining the trigger in axial alignment with the spring 24. A latch 30 is pivoted within the housing and adapted to engage at one end with the inner extremity of the trigger, while the other end engages with a connecting rod 31 secured to the plate 23.

The extremities of the arms 21 are provided with spring clamps 32, the latter being adapted to engage with the extremities of the guide arms 28 when swung inwardly toward each other.

From this construction, it is apparent that when the device is "set" in the position indicated in Fig. 1 of the drawings, a bag engaging within the pocket formed at the juncture of one of the guide arms, with the trigger, will cause the latter to rock upon its pivot 27, whereupon the latch 30 will be actuated to release the connecting rod 31, whereupon the plate 23 will, by operation of the spring 24, be retracted, drawing inwardly upon the links 22, and rocking the arms 21 upon their pivots. The clamp members 32 at the extremities of the grabber arms 21 impinge with the arcuate arm extremities 28, whereupon the bag or sack will be held firmly between the grabber and trigger arms. The bag may be readily disengaged from its position by the mail clerk upon the car, whereupon the device may be readily reset to further operate. When not in use, the grabbing device may be swung downwardly upon its pivot or may be detached entirely from the tubular standard 10 and placed in a convenient position within the car. The impact of a mail sack engaging and catching device, rocks the arm 13 and the standard 12, whereupon the detent 15 rides out of the notched portion 14 and the grabbing device and bag are swung within the car in convenient position for handling by the mail clerk.

In Figs. 6 and 7 of the drawings, I have illustrated improved means for supporting a mail sack in position to be properly collected by the above described device. In this embodiment of the invention, a post 25 is arranged beside the track, and which carries spaced brackets 36 and 37. The uppermost bracket 36 is provided with a laterally extending slot 28, within which the

innermost end of a crane arm 39 slides. This arm is held against inward movement by a collar 40. A contractile spring 41 is connected to the inner end of the crane arm 39 to normally force the latter to upward swinging position. A second arm 42 is engaged through a loop portion 43 at one end with the lowermost bracket 37 and is capable of swinging upwardly and downwardly thereon, as shown. The outer ends 75 of the arms 39 and 42 are provided with swinging hook members 44, over which rings 45 on a mail bag are adapted to engage. The springs 46 may be employed to normally hold the hook members 44 in 80 proper position. From this construction, it is apparent that a bag may be suspended properly between the crane arms, and when engaged by the above described collecting device will be readily detached therefrom. 85 Immediately upon removal of the bag from the crane arms, the lowermost arm swings downwardly upon the bracket 27 while the spring 41 moves the inner end of the crane arm 39 in a downward direction, swinging 90 the free end of the same upwardly through the slot 38.

From this construction, it is apparent that I have provided a very simple and practical device for facilitating the interchanging of the mail bags. While the above is a description of the preferred embodiments of the invention, it is apparent that various changes in the minor details of construction, combination, and arrangement of parts 100 may be resorted to, if desired, without departing from the spirit of the invention or exceeding the scope of the claims.

What is claimed is:—

1. In a device of the class described, a standard, an arm on said standard, a housing on said arm, grabber arms pivoted at the extremities of said housing and capable of swinging together at their outer ends, a plate within said housing, a contractile spring within said arm connected to said plate, links connecting the inner ends of said grabber arms to said plate, a connecting rod secured to said plate and extending beyond the same, a latch for engagement with said rod to releasably hold the same in outward position, and a trigger pivoted in said housing and projecting outwardly therefrom and adapted to actuate said latch to release said connecting rod, substantially as described.

2. In a device of the class described, a standard, an arm on said standard, a housing on said arm, grabber arms pivoted in spaced relation upon said housing and adapted to swing toward each other at their outer extremities, a contractile spring in said arm, a plate connected to the outer end of said spring, links connecting said plate to the inner ends of said grabber arms, a connect-

ing rod secured at one end to said plate, a guide for said connecting rod, a latch for holding said connecting rod at the limit of its outward movement against the tension of said spring, a trigger pivoted in said housing, and extending beyond the latter arcuate arms at the outer end of said trigger, the inner end of said trigger being adapted to engage said latch to release the same from said connecting rod, and clamp

members on the ends of said grabber arms for engagement with the extremities of said arcuate arms when swung inwardly, substantially as described.

In testimony whereof I affix my signature 15 in presence of two witnesses.

CHARLEY C. JONES.
